UNITED STATES PATENT OFFICE.

GUSTAV A. BRACHHAUSEN, OF RAIWAY, NEW JERSEY, ASSIGNOR TO THE REGINA MUSIC BOX COMPANY, OF SAME PLACE.

DESIGN FOR A CASING FOR MUSICAL INSTRUMENTS.

SPECIFICATION forming part of Design No. 32,433, dated April 3, 1900.

Application filed March 7, 1900. Serial No. 7,730. Term of patent 14 years.

To all whom it may concern:

Be it known that I, GUSTAV A. BRACHHAUSEN, a resident of Rahway, Union county, State of New Jersey, have invented and produced a new, useful, and original Design for a Casing for Musical Instruments, of which the following is a specification, reference being had to the accompanying drawings, wherein—

Figure 1 is a front view of a casing for musical instruments embodying my design. Fig. 2 is a transverse sectional view of the same, taken on the line 2 2 of Fig. 1.

The characteristic feature of my design consists of a casing for musical instruments having a front wall, with a central panel and ornamental grille adjacent to said panel.

In the drawings, *a* indicates the base of the casing proper, and said base is of curvilinear

outline on three sides, as shown in Fig. 2. Projecting from the base are upright walls *b*, which constitute the back and sides of the casing. The front wall *A* of the casing is provided with a central panel *c*, adjacent to which is located an ornamental grille *B*. The panel *c* has on each side thereof an ornamental column *d*. The walls *b* are surmounted by a top or cover *e*, projecting beyond the walls, as represented in Fig. 1.

I claim—

The design for a casing for musical instruments substantially as shown and described.

GUSTAV A. BRACHHAUSEN.
